UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER-CRINKLING MACHINE.

Application filed September 2, 1920. Serial No. 407,687.

To all whom it may concern:

Be it known that I, WILLIAM A. LORENZ, a citizen of the United States, residing in Hartford, in the county of Hartford and

5 State of Connecticut, have invented certain new and useful Improvements in Paper-Crinking Machines, of which the following is a specification.

This invention relates to means for crinkling or crêping paper, and is not only adapted for thin and weak paper, but also aims to crinkle effectively heavy and stiff grades of paper, as well as paper which it is desirable to have nearly dry at the crinkling operation.

10 It has been the practice to wet the paper thoroughly and run it around a crinkling cylinder or carrier, against which the paper has been pressed by a roll, to squeeze out the surplus water, and cause the paper to stick to the surface of the crinkling cylinder sufficiently to enable the cylinder to crush the paper edgewise against the doctor-blade, which crinkled the web and stripped it from the cylinder.

15 In order to crinkle heavy or stiff grades of paper, as well as paper which it is desired to wet only moderately, the present invention provides means for carrying the paper against the doctor-blade without being so dependent upon the adhesion of the paper to the surface of the cylinder. A belt is provided to run around the main cylinder, between the introductory side thereof and the doctor-blade. This belt is endless and holds the paper to the cylinder, so that the friction between the paper and cylinder, aided by the friction between the paper and the belt, is sufficient to advance the paper 20 with the required force against the doctor-blade, even though the paper be heavy and stiff or not saturated with water. At a point in proximity to the doctor-blade, the belt runs over a fixed support, and then 25 runs back over guide-pulleys to the introductory side of the crinkling cylinder. The belt support may be adjusted as close as desired to the doctor-blade, so as to control the character of the crinkling. Fine results 30 may be gained by forming this belt support of independently adjustable sections

Other features and advantages will hereinafter appear.

In the accompanying drawings,

Figure 1 is a plan of a crinkling machine, 55 showing the present improvements applied thereto in one form.

Figure 2 is a sectional elevation taken at about the line 2—2 of Figure 1.

Figure 3 is a plan on a larger scale, showing details of the support over which the crinkling belt turns to run up past the doctor-blade.

Figure 4 is a section taken at about the line 3—3 of Figure 1, but drawn on a larger scale.

The paper web 10 is in the form of a roll 11 mounted upon a spool 12, the rotation of said roll being retarded by a weighted friction belt 13. The web runs over a guide-roll 14 onto the main crinkling cylinder 15; steam or water being supplied to the web upon one or both sides by means of perforated pipes 16, 17. A belt 18 may also run over said guide-roll 14, the paper web 10 entering between the belt and the main cylinder 15, and running around the latter with the belt, whereby it is carried against the doctor-blade 19 and crinkled and stripped from the cylinder, as at 20; the product being carried away by delivery belt mechanism 21. The main belt, which may be wider than the paper web, returns over guide-rolls 22, 23, 24, to the introductory roll 14; and the main belt may be kept taut by the roll 23, which may be mounted upon a pair of arms 25, adjustable around a fixed shaft 26, and fastened in place by bolts 27. By reason of its taut condition, the belt causes sufficient grip between itself and the paper, and also between the paper and cylinder 15, to drive the paper with substantial force against the doctor-blade or crinkler 19, thereby successfully crinkling heavy paper, stiff paper, or paper which it is difficult to crinkle on account of the dryness thereof.

The main cylinder 15 may be driven by a pulley 28, having a pinion 29 meshing with a gear 30 on axle 31 of said cylinder; and the operation of the belt may be aided by providing roll 22 with a pinion 33 connected by pinions 34 and 35 to main gear 30.

To support the belt at the doctor-blade 19, there may be provided a fixture in the form of a rounded guide 36, which may be placed so close to the doctor-blade that the paper 5 is successfully crinkled against the blade; the latter being pointed to enter the angle or bight between the periphery of the main cylinder and the upwardly-curving belt, as seen at Figure 3.

10 The support 36 is preferably adjustable circumferentially of the main cylinder 15; being for this purpose extended backwardly in the form of a plate 37 around the cylinder 15 for a short distance, and there secured by rivets 38 to a bar 39, which is fixed by bolts 40 upon the ends of a pair of swing arms 41, the latter having hubs 41^a split at 41^b and secured by bolts 42 upon a pair of hollow studs 43, through which the 20 cylinder shaft 31 extends; said hollow studs 43 being fixed to the side frames 44 of the machine. By loosening the bolts 42, the arms 41 may be adjusted around the cylinder 15 to bring the belt support 36 closer to 25 or away from the blade 19, in which position it may be fastened by tightening the bolts 42. If desired, the plate 37 may also be extended downwardly at 45 to form a sheath for the belt; and it may have a flaring flange 46.

To secure fine adjustment of different widthwise portions of the belt as it turns up past the doctor-blade, the belt support 36 may comprise sections or leaves 47, which 35 may be integral with plate 37, and may have the form of teeth extending from said plate. Each tooth may be independently adjusted, the teeth for this purpose having individual screws 48, so that the position of the belt 40 and the character of the crinkling may be adjustably controlled throughout the width of the paper web. The screws 48 are threaded through a flange 49 formed upon the adjustable cross-bar 39.

45 It is also noted that the arms 41 may be adjusted to carry the entire structure towards or from the doctor-blade, without interfering with the individual adjustment of the screws 48; and that the latter may 50 be adjusted to secure individual variations in the sections 47, or to bring all of said sections to new positions; these sections being preferably formed of springy metal to facilitate the adjustments. The arms 25 may 55 be re-adjusted to secure the desired tautness of the belt after the adjustments of the arms 41 or of the belt-supporting sections.

Variations may be resorted to within the scope of the invention, and portions of the 60 improvements may be used without others.

Having thus described my invention, I claim:

1. The combination with a crinkling cylinder or carrier and a doctor-blade or crinkling element, of an endless belt to run

partly around the cylinder and to confine the paper against the cylinder and carry it to the crinkling element, a fixed support in proximity to said crinkling element over which said belt runs, and means to guide 70 the belt back to the introductory side of the cylinder.

2. The combination with a crinkling cylinder or carrier and a doctor-blade or crinkling element, of an endless belt to run 75 partly around the cylinder and to confine the paper against the cylinder and carry it to the crinkling element, a fixed support in proximity to said crinkling element over which said belt runs, and means to guide 80 the belt back to the introductory side of the cylinder, said belt support being adjustable relatively to the cylinder.

3. The combination with a crinkling cylinder or carrier and a doctor-blade or crinkling element, of an endless belt to run 85 partly around the cylinder and to confine the paper against the cylinder and carry it to the crinkling element, a fixed support in proximity to said crinkling element over which said belt runs, and means to guide 90 the belt back to the introductory side of the cylinder, said belt support being adjustable relatively to the cylinder and relatively to 95 the doctor-blade.

4. The combination with a crinkling cylinder or carrier and a doctor-blade or crinkling element, of an endless belt to run 100 partly around the cylinder and to confine the paper against the cylinder and carry it to the crinkling element, means to guide the paper or web into the bight of the cylinder and belt, and a support at the doctor-blade to guide the belt away from the cylinder, said belt support formed of independently 105 movable sections.

5. The combination with a crinkling cylinder or carrier and a doctor-blade or crinkling element, of an endless belt to run 110 partly around the cylinder and to confine the paper against the cylinder and carry it to the crinkling element, means to guide the paper or web into the bight of the cylinder and belt, a support at the doctor-blade to guide the belt away from the cylinder, said belt support formed of independently 115 movable sections, and means for effecting adjustment of the different sections independently of one another.

6. The combination with a crinkling cylinder or carrier and a doctor-blade, of an 120 endless belt to run partly around the cylinder, and a rounded fixed support or guide over which the belt runs in leaving the cylinder, said guide in proximity to the cylinder 125 and to the doctor-blade.

7. The combination with a crinkling cylinder or carrier and a doctor-blade, of an 130 endless belt to run partly around the cylinder, a rounded fixed support or guide over

which the belt runs in leaving the cylinder, said guide in proximity to the cylinder and to the doctor-blade, and a power-driven roll over which the belt runs in its return to the 5 introductory side of the cylinder.

8. The combination with a crinkling cylinder or carrier and a doctor-blade, of an endless belt to run partly around the cylinder, a rounded fixed support or guide over 10 which the belt runs in leaving the cylinder, said guide in proximity to the cylinder and to the doctor-blade, and a power-driven roll over which the belt runs in its return to the introductory side of the cylinder, said roll 15 in proximity to said fixed guide.

9. The combination with a crinkling cylinder or carrier and a doctor-blade, of an endless belt to run partly around the cylinder, and a rounded fixed support or guide over 20 which the belt runs in leaving the cylinder, said guide in proximity to the cylinder and to the doctor-blade, said doctor-blade having a beveled edge inserted between the crinkling cylinder and the rounded 25 guide or support.

10. The combination with a crinkling cylinder or carrier and a doctor-blade, of an endless belt to run partly around the cylinder, and a rounded fixed support or guide over 30 which the belt runs in leaving the cylinder, said guide in proximity to the cylinder and to the doctor-blade, said support adjustable circumferentially of the crinkling cylinder.

11. The combination with a crinkling cylinder or carrier and a doctor-blade, of an endless belt to run partly around the cylinder, and a rounded fixed support or guide over 35 which the belt runs in leaving the cylinder, said guide in proximity to the cylinder and to the doctor-blade, said support provided upon a plate which extends partly around the cylinder.

12. The combination with a crinkling cylinder or carrier and a doctor-blade, of an endless belt to run partly around the cylinder, a rounded fixed support or guide over 40 which the belt runs in leaving the cylinder, said guide in proximity to the cylinder and to the doctor-blade, and a pair of swinging arms upon which said support is fixed and by which its position circumferentially of the cylinder may be adjusted.

13. The combination with a crinkling cylinder or carrier and a doctor-blade, of an endless belt to run partly around the cylinder, and a rounded fixed support or guide over 45 which the belt runs in leaving the cylinder, said guide in proximity to the cylinder and to the doctor-blade, said support being divided into a series of sections provided with individual screws for independent adjustment of each section.

14. The combination with a crinkling cylinder or carrier and a doctor-blade, of an

endless belt to run partly around the cylinder, and a rounded fixed support or guide over which the belt runs in leaving the cylinder, said guide in proximity to the cylinder and to the doctor-blade, said support adjustable circumferentially of the crinkling cylinder and being divided into a series of sections provided with individual screws for independent adjustment of each section. 70

15. In a crinkling machine, the combination of a crinkling cylinder or carrier, a continuously moving belt running therearound, a doctor-blade, means for leading the paper between the cylinder and belt, to be carried thereby against the doctor-blade, and a plate 75 having a curved or rounded portion over which the belt emerges in proximity to the doctor-blade.

16. In a crinkling machine, the combination of a crinkling cylinder or carrier, a continuously moving belt running therearound, a doctor-blade, means for leading the paper between the cylinder and belt, to be carried thereby against the doctor-blade, and a plate 80 having a curved or rounded portion over which the belt emerges in proximity to the doctor-blade, said plate comprising sections individually adjustable. 85

17. The combination with a crinkling cylinder or carrier and a doctor-blade or crinkling element, of an endless belt to run partly around the cylinder and to confine the paper against the cylinder and carry it to the crinkling element, a fixed support in proximity to said crinkling element over 90 which said belt runs, and means to guide the belt back to the introductory side of the cylinder, means being provided for effecting adjustments of said support to and from the cylinder and to and from the doctor-blade. 100

18. The combination with a crinkling cylinder or carrier and a doctor-blade or crinkling element, of an endless belt to run partly around the cylinder and to confine the paper against the cylinder and carry it to the crinkling element, means to guide the belt at the bight of the cylinder and belt, and a fixed support at the doctor-blade to guide the belt away from the cylinder. 110

19. The combination with a crinkling cylinder or carrier and a doctor-blade or crinkling element, of an endless belt to run partly around the cylinder and to confine the paper against the cylinder and carry it to the crinkling element, means to guide the belt at the bight of the cylinder and belt, a fixed support at the doctor-blade to guide the belt away from the cylinder, and means to guide the belt back to the introductory side of the cylinder. 115

20. The combination with a crinkling cylinder or carrier and a doctor-blade or crinkling element, of an endless belt to run partly around the cylinder and to confine the paper against the cylinder and carry it to the 120

4
crinkling element, means to guide the belt at the bight of the cylinder and belt, and a fixed support at the doctor-blade to guide the belt away from the cylinder, said belt support formed of independently movable sections.

- 5 21. The combination with a crinkling cylinder or carrier and a doctor-blade or crinkling element, of an endless belt to run partly 10 around the cylinder and to confine the paper against the cylinder and carry it to the crinkling element, means to guide the belt at the bight of the cylinder and belt, a fixed support at the doctor-blade to guide the belt 15 away from the cylinder, said belt support formed of independently movable sections, and means for effecting adjustment of the different sections independently of one another.
- 20 22. The combination with a crinkling cylinder or carrier and a doctor-blade or crinkling element, of an endless belt to run partly around the cylinder and to confine the paper

against the cylinder and carry it to the crinkling element, a fixed support in proximity to said crinkling element over which said belt runs, a roll to which the belt runs from said support, and means gearing said roll to said cylinder.

- 25 23. The combination with a crinkling cylinder or carrier and a doctor-blade or crinkling element, of an endless belt to run partly 30 around the cylinder and to confine the paper against the cylinder and carry it to the crinkling element, a fixed support in proximity to said crinkling element over which 35 said belt runs, a roll to which the belt runs from said support, means gearing said roll to said cylinder, and means for guiding the belt back to the introductory side of the 40 cylinder.
